UNITED STATES PATENT OFFICE.

WALTER JONES, OF NEW BRUNSWICK, NEW JERSEY, ASSIGNOR, BY MESNE ASSIGNMENTS, TO BRUNSWICK-KROESHELL COMPANY, OF NEW BRUNSWICK, NEW JERSEY, A CORPORATION OF NEW JERSEY.

KNUCKLE-JOINT CONNECTION.

1,427,392.

Specification of Letters Patent. Patented Aug. 29, 1922.

Application filed August 10, 1921. Serial No. 491,105.

To all whom it may concern:

Be it known that I, WALTER JONES, a citizen of the United States, residing at New Brunswick, in the county of Middlesex, in the State of New Jersey, have invented certain new and useful Improvements in Knuckle-Joint Connections, set forth in the following specification.

The invention relates to an improvement 10 in knuckle joint connections for pistons and rods, and more particularly to an improvement in the knuckle joint connection between the piston and eccentric rod or strap disclosed in U. S. Patent No. 899,583, dated 15 September 29, 1908.

The knuckle joint connection between the piston and the eccentric rod or strap shown in that patent comprises a cylindrical head formed on one end of the eccentric strap 20 and received within a transverse bore in the piston. The construction and arrangement of this knuckle joint connection enable the parts to continue in use for long periods without repair or replacement. When the 25 parts have become worn by reason of long use, however, there is no provision for taking up the lost motion. The object of the present invention is to produce an improved knuckle joint connection between pistons 30 and eccentric rods or straps having provision whereby compensation for wear may be made without dismantling the machine. To this end the invention consists in the improved knuckle joint connection herein- 35 after described and particularly pointed out in the appended claims.

The preferred form of the invention is illustrated in the accompanying drawings in which Fig. 1 is a vertical section through 40 the improved knuckle joint connection; Fig. 2 is a side elevation of the parts shown in Fig. 1; and Fig. 3 is a detail of a modified form of eccentric strap head.

The improved knuckle joint connection 45 for pistons and eccentric rods or straps, as illustrated in the drawings, comprises in general an eccentric strap 5 having at its upper end a cylindrical head 6 received within a bore 7 formed transversely in the lower 50 part of the cylinder 8. The head is provided with the longitudinal grooves 9 for lubrication. These parts may be of any usual or preferred construction, and for purposes of illustration and description are

shown substantially as disclosed in said 55 patent. As the piston reciprocates in the cylinder of the machine or pump, the head of the eccentric rod or strap oscillates in the transverse bore in the piston. Inasmuch as the reciprocating motion is transmitted to 60 the piston by the eccentric strap, it is necessary that there be no lost motion between the head of the eccentric strap and the piston.

The improved means of the present invention for taking up or compensating for lost motion between the eccentric strap and the piston comprises a pair of truncated cones 10 and 11 received in tapering holes bored longitudinally in the head 6 of the eccentric 65 strap, as clearly shown in Fig. 1. The holes in the head of the eccentric strap taper toward the central portion 12 thereof. Each cone is of such length that when it is inserted in its corresponding tapered bore in 70 the eccentric strap head it projects therefrom sufficiently to provide for considerable expansion of the eccentric strap head. In order that the head may be expanded to 75 take up or compensate for lost motion it is provided on its upper side with a longitudinal slot 13. The eccentric head is subject to greater wear on its top side than on its lateral sides. In order that the head when 80 expanded to compensate for wear, may expand more at the top than at the sides, the lateral sides of the tapered holes are cut away or relieved at 18, as shown in the modified form of eccentric head illustrated in 85 Fig. 3. When the cones are drawn toward 90 each other to expand the head, the expanding pressure is exerted on the points 19 and thus the extra wear on the top is readily taken up.

The eccentric strap head is expanded by 95 drawing the cones 10 and 11 toward each other. For this purpose a screw 14 is loosely received in the cone 11 and is threaded into the cone 10. To take up lost motion in the threads a spring collar 15 is inserted between the head 16 of the screw and the bottom of the bore in which the screw head is received.

It will be observed that the construction of the means for taking up or compensating 105 for lost motion between the piston and the eccentric strap is such that the eccentric strap head may be kept substantially in its

true cylindrical form, thereby assuring smoothness and efficiency in operation. The screw 14 may be reached to draw the cones toward each other to expand the eccentric strap head to take up lost motion by passing a square-ended wrench through a hole cut in the side of the cylinder for that purpose. The head 16 of the screw is provided with a broached hole 17 to receive the squared end 10 of the wrench.

It will be understood that the present invention provides a simple and efficient means for taking up or compensating for lost motion between pistons and eccentric rods or straps. The adjustment means is so constructed that the necessary adjustment may be made without dismantling any of the parts of the machine or pump. Thus a great saving of time and labor is secured; and 20 moreover, the machine or pump may be kept in nice adjustment at all times because of the facility with which the adjustment may be made.

Having thus described the invention, what 25 I claim as new is:—

1. A knuckle joint connection for pistons

and rods comprising a cylindrical head having a longitudinal slot received within a transverse bore in the piston, said head having tapered holes tapering toward the middle of the head, a cone in each tapered hole, and a screw connecting the cones whereby they may be drawn toward each other to expand the head to take up lost motion between it and the transverse bore in the piston. 30

2. A knuckle joint connection for pistons and rods comprising a cylindrical head having a longitudinal slot received within a transverse bore in the piston, said head having tapered holes tapering toward the middle of the head, a cone in each tapered hole, a screw connecting the cones whereby they may be drawn toward each other to expand the head to take up lost motion between it 40 and the transverse bore in the piston, said tapered holes being relieved at their lateral sides so that greater expanding pressure may be communicated to the top side of the cylindrical head than to the lateral sides 45 thereof.

WALTER JONES.
